COMBINED CLOSURE AND GAUGE FOR A FLUID SYSTEM

Eugene L. Kilbourn, Marshall, Mich., assignor to
Progressive Dynamics, Inc., Marshall, Mich.

Filed July 12, 1965, Ser. No. 86,117

Term of patent 14 years

(Cl. D91—1)

FIG. 1

FIG. 2

FIG. 3

FIG. 4

FIG. 1 is a perspective view of a combined closure and gauge for a fluid system as seen from the front and side,

FIG. 2 is an enlarged, side elevation thereof,

FIG. 3 is a front elevation thereof, and

FIG. 4 is a side elevation thereof.

The dominant features of my design reside in the portions shown in full lines, the broken line disclosure in FIGS. 1 and 2 being for illustrative purposes only.

I claim:

The ornamental design for a combined closure and gauge for a fluid system, as shown and described.
